UNITED STATES PATENT OFFICE.

OSCAR H. THELEEN, OF KENOSHA, WISCONSIN, ASSIGNOR TO FROST MANUFACTURING COMPANY, OF KENOSHA, WISCONSIN, A CORPORATION OF WISCONSIN.

FLUSHING MECHANISM.

Application filed April 19, 1923. Serial No. 633,103.

To all whom it may concern:

Be it known that I, OSCAR H. THELEEN, a citizen of the United States, residing in Kenosha, county of Kenosha, and State of Wisconsin, have invented certain new and useful Improvements in Flushing Mechanisms, of which the following is a specification.

This invention relates to improvements in flushing mechanisms, and refers more particularly to a flush tank lever mechanism for use in low down flush tanks.

Among the objects of the invention are to provide a mechanism which is sturdy of construction, easily operated, necessitating little adjustment and repair due to the fact that the strain upon the parts is relatively slight; to provide an inexpensive and simple structure which may be installed without the use of mechanical devices.

This invention is an improvement on my application Serial No. 452,092 filed March 14th, 1921.

Fig. 1 is a vertical section through the flush tank showing the general arrangement of the parts. Fig. 2 is a sectional plan view taken through the center of the rotating shaft. Fig. 3 is a view of a modified form of construction in which the shaft is prevented from complete rotation. Fig. 4 is a detail view of the link connection between the lever and crank shaft.

Referring to the drawings 1 designates a flush tank which is equipped with an outlet pipe 2 controlled by a valve 3. This outlet flow is also connected to a standpipe or overflow pipe 4 to which is attached a guide support or bracket 5, which serves to guide the stem 6 of the valve. This valve stem 40 is connected with a lever 7 pivoted at 8 by means of a link connection 9. The upper end of the pivoted lever, or that end opposite to the portion connected to the valve, has an angularly disposed extension 7^a which 45 is drilled to provide for the insertion of the end of a link 10 which connects the upper angularly disposed extension to the crank 11 formed in the end of the crank shaft 12.

The crank shaft shown in Fig. 2 is rotatable in the threaded boss 13 which forms a part of the bracket 13^a. That portion of the boss which passes through the wall of the tank 1 is shaped square, and fits in a square hole in the tank, thus preventing rotation 55 of the boss. The outer end of the boss is

threaded to accommodate a holding nut 14 which is screwed down onto the washer 15 forming a flange against the side of the tank. At the outer extremity of the shaft 12 is fixed an angle cap 16 into which is 60 screwed an operating handle 17, which may be of wood, porcelain, or other vitrified material. On the bracket 13^a is a stud 18, upon which is pivoted the lever 7, which is held in place by means of a cotter pin or other 65 suitable holding means.

To operate the valve, the handle may be rotated in either direction, the crank pulling downwardly upon the angularly related extension 7^a of the lever 7 through the link 10, 70 and raising the opposite end of the lever which raises the valve 3 from its seat and permits the outflow of water through the pipe 2 and flushing of the mechanism.

In the modified form of construction, on 75 the bracket 13^a is positioned a stop member shown at 13^b, which is bent in a manner to extend over the top of the lever 7, and thus limit its movement. This stop while permitting the raising of the valve, prevents 80 the entire rotation of the handle 17, that is, the handle may be moved in either direction from its depending vertical position, through a considerable angle, but is prevented from complete rotation. 85

The advantage of this type of mechanism, lies in the details of its construction, and particularly in the character of the link connection shown at 10. This link comprises a rod such as that shown in Fig. 4 being 90 bent near both ends at right angles to the stock of the link to form bearing portions for the lever and crank, the extremities of the link beyond the respective bearings being again bent substantially at right angles 95 and parallel to the stock of the link to form the locking or holding element. This link is preferably of non-corrosive metal such as brass, copper or like materials, and of such diameter as to have sufficient rigidity to prevent deformation with any strain which may be imposed by the turning of the operating handle. 100

In addition to the simplicity of the mechanism, it is exceedingly facile in operation, 105 as there are no frictional cam surfaces normally utilized in this type of construction to function the valve, and in addition the mechanism may be assembled without the need of riveting or use of screws, bolts or 110

other like mechanical contrivances. The link permits free rotation of the handle in the mechanism such as that shown in Fig. 1 and the downwardly disposed ends of the link 10 prevent the mechanism from coming apart and assures the permanent relative positioning of the different parts.

The construction differs from the mechanism shown in my previous application mentioned heretofore, in that in place of a two part shaft which is assembled telescopically to form a unitary structure, a single solid shaft is utilized.

Further, it has been found for certain uses, particularly in public buildings, that in some cases, it is objectionable to have a completely rotating handle, and in order to slightly vary the construction, the stop 13^b shown in Fig. 3 has been positioned above the lever to limit the throw of the lever and the angle through which the handle 17 can be rotated in order to operate the valve.

The advantages of assembly, the permanence, simplicity and inexpensiveness of the parts in addition to the ease and effectiveness of operation, and ruggedness, make this device admirably suitable to the uses to which it is put.

I claim as my invention:

- 30 1. In a flush tank mechanism, the combination with a solid shaft actuated by a handle, and having a crank, of a pivoted lever, a link between the crank and lever, a valve communicating with the lever adapted to be functioned by the actuation of the handle, said link being disengageable with the lever and crank with the removal of the lever from its pivot, and comprising a stock or body portion having angular connecting portions and substantially parallel extensions, the latter extending in the same direction.
- 40 2. In a flush tank mechanism, the combination with a solid rotatable shaft actuated by a handle, and having a crank, of a pivoted lever, a link connecting the crank and lever, a valve communicating with the lever and adapted to be functioned by the actuation of the handle, said link comprising a

bent rod having substantially right angle connections with substantially parallel extensions the latter extending in the same direction, serving to lock the related parts in position and readily detachable from the crank and lever with the removal of the lever from its pivot.

3. In a flush tank mechanism, the combination with a solid shaft actuated by a handle, and having a crank, of a pivoted lever, a valve communicating with said lever, and a link connection between crank and lever whereby the valve is functioned by the actuation of the handle, said link comprising a rod bent at right angles with its ends to form bearings for the crank and lever, and locking means formed by bending the extremities of the rod in the same direction at an angle to the bearings.

4. In a flush tank mechanism, the combination with a solid rotatable shaft actuated by a handle, and having a crank, of a pivoted lever, a valve actuated by said lever, and a link connection between crank and lever whereby the valve is functioned by the actuation of the handle, said link comprising a rod bent at right angles with its ends to form bearings for the crank and lever, and locking means formed by bending the extremities of the rod substantially parallel with the link, said extremities extending in the same direction.

5. In a flush tank mechanism, the combination with a solid rotatable shaft actuated by a handle, and having a crank, of a pivoted lever communicating with a valve, a link connection between crank and lever whereby the valve is functioned by the actuation of the handle, said link comprising a rod bent at substantially right angles, with its ends to form bearings for the crank and lever, holding means formed by bending the extremities of the rod beyond the bearings in the same direction to limit the horizontal movement of the related parts and to prevent disengagement.

OSCAR H. THELEEN.
